[57] CLAIM

The ornamental design for light bulb travel carrier, as shown and described.

DESCRIPTION

FIG. 1 is an exploded perspective view of a light bulb travel carrier showing my new design, the broken lines partially showing a pair of light bulbs being for illustrative purposes only and forming no part of the claimed design;

FIG. 2 is a side elevational view thereof, slightly rotated counter clockwise, the front and rear being substantially identical except for the anchor loop and hand strap;

FIG. 3 is an exploded side elevational view thereof shown rotated slightly;

FIG. 4 is a top plan view thereof;

FIG. 5 is a bottom plan view thereof;

FIG. 6 is an exploded front elevational view of an alternate embodiment of the design shown in FIG. 1, the broken lines partially showing a light bulb being for illustrative purposes only and forming no part of the claimed design;

FIG. 7 is a bottom plan view of the cover component of the embodiment shown in FIG. 1, the bottom plan view of the second embodiment being identical;

FIG. 8 is a top plan view of the central component of the embodiment shown in FIG. 1, the bottom being identical in the first embodiment, and being planar and unadorned in the second embodiment;

FIG. 9 is a side elevational view of FIG. 6 shown in an assembled position; and,

FIG. 10 is a bottom plan view of FIG. 9.
